COMBINED DISHWASHER AND FAUCET FIXTURE

Raymond W. Young, Toledo, Ohio, assignor to Gerity
Products, Inc., Toledo, Ohio, a corporation of
Michigan

Filed Sept. 14, 1964, Ser. No. 81,721

Term of patent 14 years

(Cl. D91—3)

FIG. 1

FIG. 2

FIG. 3

FIG. 4

FIG. 5

FIGURE 1 is a perspective view of a combined dishwasher and faucet fixture, showing my new design;

FIGURE 2 is a front elevational view thereof;

FIGURE 3 is a top plan view thereof, the faucet spout being fragmentarily shown for convenience of illustration;

FIGURE 4 is a side elevational view thereof; and

FIGURE 5 is a fragmentary sectional view taken along line 5—5 of FIGURE 2.

I claim:

The ornamental design for a combined dishwasher and faucet fixture, substantially as shown and described.
